ROTARY INTAGLIO PRINTING MACHINE

Franz Heller, Mount Vernon, and Richard A. Krahmer, Yonkers, N. Y., assignors to R. Hoe & Co., Inc., New York, N. Y., a corporation of New York

Application August 28, 1941, Serial No. 408,616

8 Claims. (Cl. 101—157)

This invention relates to rotary intaglio printing machines and more particularly to an improved doctor blade mechanism for such machines.

Each printing cylinder of an intaglio printing machine is commonly provided with a flexible metal doctor blade arranged to have an edge thereof in engagement with the surface of the printing cylinder which rotates in an ink fountain, and to be pressed thereagainst with the proper amount of tension to insure removal of surplus ink from the cylinder surface. It is desirable that the pressure of the doctor blade be readily and delicately adjustable, and it is also desirable that the blade be arranged to be swung away from the printing cylinder to permit accessibility to adjacent machine parts, and to be again disposed and locked in operative position without disturbing its adjustment in respect to the surface of the cylinder.

One object of this invention is to provide an improved form of doctor blade mechanism for intaglio printing machines whereby the pressure of the doctor blade upon the surface of the printing cylinder may be readily and delicately adjusted, and the doctor blade may be moved to and from operating position without disturbing the adjustment.

Another object is to provide a doctor blade mechanism wherein provision is made to swing the doctor blade away from the cylinder and adjacent machine parts and mechanisms a relatively large amount whereby such parts and mechanisms will be conveniently and readily accessible.

A further object is to improve the form of doctor blade mechanism shown in Patent No. 2,097,791 by providing a blade locking means which will not require axial movement to permit the swinging of the blade supporting arms away from the cylinder, and wherein features are provided which increase its efficiency.

Other objects are to provide a cushioning means to prevent the blade abruptly striking the cylinder when it is swung into engagement therewith, an adjustable stop means to limit its movement in that direction, and combinations of these features in a doctor blade mechanism whereby each one may assist the operation and enhance advantages of the others.

It is also an object of this invention to provide a doctor blade mechanism, for an intaglio printing machine, of generally improved construction, whereby the same will be simple, durable and in-

expensive in construction, as well as convenient, practical, serviceable and efficient in its use.

With the foregoing and other objects in view, which will appear as the description proceeds, the invention resides in the combination and arrangement of parts, and in the details of construction hereinafter described and claimed.

The preferred embodiment of the invention is illustrated in the accompanying drawings, wherein:

10 Figure 1 is a sectional view of a portion of an intaglio printing machine and which shows an end view of a doctor blade mechanism embodying the features of this invention;

15 Figure 2 is a top plan view of the doctor blade mechanism looking in the direction of arrow 2 in Figure 1;

20 Figure 3 is a side view of the doctor blade mechanism looking in the direction of arrow 3 in Figure 1;

Figure 4 is a sectional view of the mechanism taken on the line 4—4 of Figure 2;

Figure 5 is a sectional view taken on the line 5—5 of Figure 2; and

25 Figure 6 is a sectional view taken on the line 6—6 of Figure 2.

Referring to the drawings, a doctor blade mechanism embodying the features of the invention is shown in Figure 1, in association with a printing cylinder 11 of an intaglio printing machine. An impression cylinder 12 cooperates with the printing cylinder 11 to print on a web 13 running between these cylinders. The printing cylinder 11 is provided with the usual engraved printing surface 14 and is mounted to be rotated in an ink well or fountain 15 where ink adheres to its peripheral surface 14 and is subsequently transferred to the web 13. A doctor blade 16, made of comparatively thin and flexible metal, is supported by the mechanism of this invention and is disposed in engagement with the surface 14 of the cylinder 11 to remove surplus ink therefrom.

The doctor blade 16 extends axially along the cylinder 11 and is securely clamped by means of screws 17 between bars 18 and 19. The upper bar 18 is provided with a flange 21 along its rear edge and is secured in grooves 22 provided in corresponding ends of each of a pair of arms 24 and 25 (Figure 2), and abuts against an end surface 26 provided on an intermediate arm 27. At each of the arms 24 and 25, the flange 21 is clamped within the groove 22 by a set screw 28, and is located upon the end surface 26 on the arm 27 by an adjusting screw 29. The arms 24, 25 and 27 are mounted upon a shaft 31, the arms

24 and 25 being freely rotatable on the shaft 31, and the arm 27 being releasably clamped thereto by screws 32, whereby it may be rotatably adjusted about the shaft 31.

The shaft 31 is journaled at each end in bearing supports 33 and 34, and intermediate its ends, in a bearing support 35. The bearing supports 33, 34 and 35 are each suitably mounted upon a reciprocable base plate 36, which in turn is supported upon a stationary machine frame member 37. Means is herein shown whereby the bearing supports 33, 34 and 35 may be adjusted transversely of the base plate 36, these being hand screws 38 (Figure 1). The adjusting mechanism controlled by the hand screws 38 is not used during ordinary operation of the machine unless it is desired to change the angle of contact of the doctor blade on the cylinder, or to position the blade to suit a printing cylinder having a different diameter, and hence on machines where the same size cylinder is always used, the adjusting means controlled by the hand screw 38, may be omitted. The base plate 36 may be reciprocated axially in respect to the cylinder 11 along ways 39, provided on the stationary machine frame member 37, by known means not shown. The shaft 31 is adapted to be turned manually by a handle 41 (Figure 2), keyed to the shaft 31, preferably adjacent the intermediate bearing support 35.

The end arms 24 and 25 which carry the bars 18 and 19 are connected to rocker arms 42 and 43 respectively by means of adjusting screws 44 (Figures 2 and 6). The screws 44 are rotatable freely in posts 46 carried by the arms 42 and 43 and have handles 45 secured to them by pins 47. Thrust collars 40 are pinned or otherwise secured to the screws 44, and with the handles 45 prevent axial motion of the screws 44 with respect to the posts 46. The screws 44 are screw threaded into studs 48 carried by the arms 24 and 25. Rotation of the screws 44 by the handles 45 will adjust the arms 24 and 25 with respect to the rocker arms 42 and 43. The arms 42 and 43 are releasably clamped, by means of screws 49 (Figure 5) to the shaft 31, and thus may be rotatively adjusted thereon.

Movement of the rocker arms 42 and 43 to swing the arms 24 and 25, and the doctor blade 16 toward the cylinder 11 is limited by adjusting screws 50 having lock nuts 51 associated therewith. The screws 50 are screw threaded through lugs 52 provided on the rocker arms 42 and 43, and their inner ends 53 engage pins 54 extending from the adjacent sides of the respective bearing supports 33 and 34. The doctor blade 16 may thus be accurately adjusted with respect to the cylinder 11 by manipulating the adjusting screws 44, and the limit screws 50 are set in engagement with the pins 54 while the arms 42 and 43 are locked in operating position by means to be hereinafter described. Coiled springs 55 are disposed about each screw 50 and in counterbores 56 formed in the rocker arms 42 and 43, and act to bias the respective arms away from the pins 54. The springs 55 act as cushioning means to prevent harsh engagement of the blade 16 with the engraved surface 14 of the cylinder 11, and prevent damaging the cylinder by the doctor blade when it is swung toward the cylinder by manipulation of the handle 41. Engagement of the springs 55 and the adjusting screws 50 with the pins 54 also serve as an effective stop for the doctor blade mechanism to prevent injury thereto should it be moved into

operating position while the printing cylinder is removed from the fountain.

Means including a handle 58 (Figures 3, 4 and 5), a short shaft 57, and a slotted sleeve 58 is provided at each standard 33 and 34. The shafts 57 are journaled in the adjacent and associated standards 33 and 34, and have handles 56 secured at one end, and sleeves 58 secured to the other end. The sleeves 58 are provided with deep slots 59 forming rocking latches 61 adapted to engage pins or latch engaging members 62, mounted in and extending from adjacent sides of the rocker arms 42 and 43 to lock the blade 16 in its cylinder engaging position. The axes of the shafts 57 and the axes of the pins 62 are located equidistant from the axis of the shaft 31 so that, as the rocker arms 42 and 43 are swung about with the shaft 31, the pins 62 enter the slots 59 in the sleeves 58. By manipulation of the handles 56 to rotate the shafts 57, the sleeves are rotated causing the pins 62 to be engaged by the latches 61, and drawing the arms 42 and 43 toward the cylinder 11, thus securely locking the blade 16 in engagement therewith. A pin 63 extending from each of the standards 33 and 34 limits the movement of the handles 56 in locking direction. Rotation of the shafts 57 in the opposite direction, by moving the handles 56 to the position shown in dotted lines in Figure 4, will cause the latches 61 to free the pins 62 and permit the rocker arms 42 and 43 with the blade carrying arms 24 and 25, to be swung away from the cylinder 11 and into the position indicated by the dotted lines in Figure 1, giving free access to the interior of the fountain 15.

The cushioning springs 55, together with a leaf spring 64 (Figure 1), reacting against the blade clamping plate 19, act to raise the blade 16 from the cylinder 11 when the latches 61 are turned to releasing position and insure that no damage to the cylinder will occur should the cylinder inadvertently be turned in the reverse direction before the blade 16 has been swung away. An ink deflector 65 (Figure 1) shown in association with the doctor blade 16 and the cylinder 11, has an edge 66 disposed closely adjacent the periphery of the cylinder 11 to remove a portion of the excess ink therefrom, and thus reduce the amount of ink which the blade 16 is required to handle. This deflector 65 extends the entire length of the blade 16 and is provided with openings 67 which allow the ink removed by the blade 16 to return to the fountain 15. The deflector 65 also has a flange 68 depending therefrom to direct the ink which it removes from the cylinder back into the fountain.

From the foregoing description, it will be seen that in moving the doctor knife mechanism from the full line position shown in Figure 1 to the position shown in dotted lines, the handles 56 are first swung clockwise as seen in Figure 1 into the position shown in dotted lines in Figure 4. This results in turning the latches 61 through approximately 180° so that the openings of the slots 59 are turned directly opposite to the position shown in Figure 5, and the pins 62 are then free to move clockwise and out of the slots 59 when the handle 41 is swung clockwise to rotate the shaft 31 and swing the entire doctor blade mechanism to the dotted position of Figure 1. In the operation of moving the doctor blade from inoperative to operative position, the reverse sequence of operation is followed, by first turning the handle 41 counter-clockwise to move the doctor blade to a point adjacent the cylinder,

and the handles 58 are then manipulated to turn the bushings 59 through approximately 180° in a counter-clockwise direction, to the "lock-up" position shown in Figure 5, this motion of the bushings resulting in a camming action of one side of the slots 59 against the pins 62, which results in producing the desired operating pressure of the doctor blade against the cylinder.

It will be understood that the invention may be embodied in other specific forms without departing from the spirit or essential attributes thereof, and it is therefore desired that the present embodiment be considered in all respects as illustrative and not restrictive.

What is claimed is:

1. In a doctor blade supporting mechanism for a printing machine, the combination of a doctor blade holder, a pivotally mounted arm for supporting the doctor blade holder and to move the blade into and out of engagement with the surface of a printing cylinder, and a latch engaging member connected to the pivotally mounted arm, with means to lock the pivotally mounted arm in position to hold the blade in engagement with the surface of the cylinder, including a latch supported to rock on a relatively fixed axis and in a single plane and adapted to engage the latch engaging member, the said latch being movable in one direction to press the blade against the cylinder and lock it in operating position, and movable in the opposite direction to release the blade and permit passage of the latch engaging member and the pivotally mounted arm, so the blade may be swung away from the cylinder.

2. In a doctor blade supporting mechanism for a printing machine, the combination of a doctor blade holder carrying a doctor blade, a pivotally mounted arm for supporting the doctor blade holder and to move the blade into and out of engagement with the surface of a printing cylinder, and a latch engaging member connected to the pivotally mounted arm, with means to lock the pivotally mounted arm in position to hold the blade in engagement with the surface of the cylinder, including a latch supported to rock on a relatively fixed axis and in a single plane and adapted to engage the latch engaging member, the said latch being movable in one direction to press the blade against the cylinder and lock it in operating position, and movable in the opposite direction to release the blade and permit passage of the latch engaging member and the pivotally mounted arm so the blade may be swung away from the cylinder, and resilient means movable with the pivotally mounted arm to cushion the engagement of the blade with the cylinder surface when the blade is swung into contact therewith.

3. In a doctor blade supporting mechanism for a printing machine, the combination of a doctor blade holder, pivotally mounted arms for supporting the doctor blade holder and to move the blade into and out of engagement with the surface of a printing cylinder, rocker arms each having a latch engaging member, and adjustable means to connect the rocker arms to the pivotally mounted arms to vary the pressure of the blade on the cylinder, with means to lock each rocker arm and pivotally mounted arm in position to hold the blade in engagement with the surface of the cylinder, including a rotary latch adapted to engage a said latch engaging member and rotatable in one direction to engage and exert pressure on the latch engaging member thus engaged and thereby press the blade against the cylinder and lock it in position, and rotatable in

the opposite direction to relieve pressure from and disengage the latch engaging member, to release the blade and permit it to be swung away from the cylinder.

5. In a doctor blade supporting mechanism for a printing machine, the combination of a doctor blade holder, pivotally mounted arms for supporting the doctor blade holder and to move the blade into and out of engagement with the surface of a printing cylinder, rocker arms each having a latch engaging member, and adjustable means to connect the rocker arms to the pivotally mounted arms to vary the pressure of the blade on the cylinder, with means to lock each rocker arm and pivotally mounted arm in position to hold the blade in operating engagement with the surface of the cylinder, including a rotary latch adapted to engage a said latch engaging member and rotatable in one direction to engage and exert pressure on the latch engaging member thus engaged and thereby press the blade against the cylinder and lock it in position, and rotatable in the opposite direction to relieve pressure from and disengage the latch engaging member, to release the blade and permit it to be swung away from the cylinder, and resilient means movable with the pivotally mounted arm to cushion the engagement of the blade with the cylinder surface when the blade is swung into contact therewith.

5. In a doctor blade supporting mechanism, a blade holder, a first arm for supporting the blade holder, a shaft upon which the first arm is mounted, a second arm fixed to the shaft, means to rock the shaft, adjustable connecting means between the arms whereby relative movement between them may be obtained to vary the pressure of the blade on the cylinder, means to cushion the movement of the arms toward the cylinder, adjustable means to limit the movement of the arms toward the cylinder, and locking means to draw the arms toward the cylinder against the action of the cushioning means and to a position as limited by the limiting means.

6. In a doctor blade mechanism, a blade, a first arm for supporting the blade, a rock shaft upon which the first arm is rotatably mounted, a second arm fixed to the shaft to rock therewith, adjustable connecting means between the arms whereby relative movement therebetween may be effected to vary the pressure of the blade on the cylinder, means carried by the second arm and reacting against a stationary part to bias the arms and with them the blade away from the cylinder, and means to draw the arms toward the cylinder to engage it by the blade, against the action of the biasing means and to lock the arms in such position.

7. In a doctor blade mechanism, a blade, a first arm for supporting the blade, a rock shaft upon which the first arm swings, a second arm fixed to the shaft to rock therewith, adjustable connecting means between the arms whereby relative movement between them may be effected to vary the pressure of the blade on the cylinder, means carried by the second arm and reacting against a stationary part to bias the arms and with them the blade away from the cylinder, means to draw the arms toward the cylinder to engage it by the blade, against the action of the biasing means and to lock the arms in such position, and adjustable means to limit the movement of the arms toward the cylinder by the arm locking means.

8. In a doctor blade mechanism for a printing

machine having a cylinder, a doctor blade, a first arm for supporting the blade, a shaft upon which the first arm is freely rotatable, a second arm to move the blade toward and away from the cylinder adjustably connected to the first arm for relative movement therebetween, the second arm being connected to the shaft, a stationary standard in which the shaft is journaled, a latch engaging member carried by and extending from the second arm, a latch member journaled in the standard and rotatable on an axis disposed on the arc of travel of the latch engaging member as it rotates with the shaft, means

to rock the member in one direction to engage the latch engaging member to draw the arms toward the cylinder, an adjustable stop member carried by the second arm and adapted to engage a part extending from the stationary standard to limit the movement of the arms toward the cylinder, and spring means acting to bias the arms in a direction away from the cylinder and to cushion the engagement of the stop means with the part extending from the standard.
